BOWLING PIN DUSTER

Joseph I. Shulevitz, Detroit, Mich., assignor to Cadillac Overall Supply Company, Detroit, Mich.
Filed Nov. 9, 1961, Ser. No. 151,325
2 Claims. (Cl. 273—43)

This invention relates to a bowling pin duster and more particularly to a means for dusting bowling pins as the pins are being carried through and handled by an automatic bowling pin setting machine.

In commercial bowling alleys, it is conventional to use mechanical bowling pin setting machines, such as are illustrated in the patents to Dumas 2,821,395 and Zuercher 2,815,954. These machines gather the bowling pins, after they are struck down by the bowling ball, carry these pins back to the proper positions upon the end of the wood floor of the bowling lane, and into the pit of the alley, and then set up these pins in their proper positions so that the bowler may again roll a ball towards them.

These automatic pin setters are sensitive to dust and dirt, which, to some extent, they receive from the pins. The pins in rolling about after being struck down acquire coatings of dust and dirt which they carry through to the pin setting mechanism. This dust and dirt ultimately causes the pin setter to malfunction, thus requiring frequent repair and adjustment.

Hence, it is highly desirable to dust each pin after it is struck down but before it enters the conveying mechanism of the automatic pin setter and thus avoid the carrying of dust and dirt into the mechanism. However, the nature of the mechanism and the space requirements are such that it has been considered to be impractical to dust each pin prior to its entering the automatic pin setter mechanism for resetting.

Thus, the object of this invention is to provide a bowling pin duster mechanism which will automatically dust each pin after it is struck down by a bowling ball but before it is carried through to the pin resetting mechanism thereby substantially to reduce the carrying of dirt and dust into the pin setter.

A further object of this invention is to provide a bowling pin duster which includes as its main dusting element, an endless cloth band so arranged and formed that it will dust each pin as the pin rolls towards the pin setter mechanism, wherein the cloth belt will regularly shift and advance its position so as repeatedly to present clean surfaces to the pins, and wherein the band may be easily removed and replaced by a similar band after it has become dirty.

Still a further object of this invention is to utilize the shock imparted by a bowling ball being stopped by the pin setter ball bumper and also the frictional drag of the conveyor belt normally used to convey the pins from the wood floor of the bowling lane to the pin setting mechanism together as the means to shift and advance the dusting cloth to change its dusting portion.

These and other objects and advantages of this invention will become apparent upon reading the following description, of which the attached drawings form a part.

In these drawings:

FIG. 1 is a perspective view of the pit portion at the end of a bowling alley, but with most of the automatic pin setter mechanism being omitted for illustration purposes.

FIG. 2 is a rear end elevational view of parts at the end of the lane, and

FIG. 3 is a side view taken in the direction of arrows 2—2 of FIG. 2.

FIG. 4 is a perspective view of certain parts including the cloth duster band.

2

In FIG. 1, the numeral 10 generally designates the pit end of a bowling alley, that is, the end most remote from the bowler and thus, the place where the bowling pins are arranged in their standing pattern to receive the 5 bowling ball rolled by a bowler. The lane includes a wood floor 11 upon which the pins are set up in predetermined places and upon which the ball rolls. At the 10 end of the lane floor 11 is a pit containing a horizontal, constantly moving, endless conveyor belt 12 which carries downed pins P from the floor 11 into the automatic pin setting mechanism (not illustrated) for replacement upon the predetermined spots S on 11.

A conventional pin setter mechanism used herewith includes a horizontal bar 13 arranged considerably above 15 and transverse to the belt 12 and mounted upon a support frame 14, which is part of the pin resetting machine, by means of resilient bushings or washers 15 which non-rotatably receive the opposite ends of the bar 13 and are 20 in turn supported upon the support frame 14. These referenced parts 13—14—15 and others hereafter referred to form part of the mechanism of this application as well as part of a conventional pin setting machine.

Located beneath bar 13, a short distance above the belt 12, is a horizontally arranged bumper plate or strip 16 25 against which the bowling ball B rolls as it completes its travel down the lane. After striking the bumper 16, the ball stops and rolls off to one side of the lane where it is picked up by a ball return mechanism (not illustrated). Corresponding parts may be found in Dumas 2,821,395 30 who shows a belt 326, a bumper or cushion 88 on a shaft (unnumbered) for actuating a pit switch 90 which starts a sweep motor 94 and rotates a shaft 236. The unnumbered shaft of Dumas, supporting the cushion 88, may be considered the same as shaft 13 hereof.

35 Corresponding parts may also be found in Zuercher 2,815,954 whose bumper S-38 is supported from shaft 42 by arms 40. Shaft 42 may be considered the same as shaft 13 hereof.

The bumper is rigidly connected to the bar 13 by means 40 of brackets or arms 17 so that the shock or impact of the ball striking the bumper is transmitted to the bar 13. In the structure illustrated, the impact of the ball against the bumper 16 will cause the bumper to move rearwardly a slight amount, from $\frac{1}{8}$ inch to $\frac{1}{2}$ inch due to the fact 45 that the bar 13, mounted in the resilient, rubber-like bushings 15, twists the bushings slightly under impact. Such movement of bar 13 may be relied on to activate a pit switch, as in Dumas.

50 So far the parts described are old and well-known. The means for constantly dusting the pins as they pass from the alley 11 upon the belt 12 to the pin setting mechanism, consists essentially of an endless cloth belt 20 (see FIG. 4) which is preferably made of a dust attractive cloth, such as is commonly available on the market today 55 and known as silicon treated cloth. The particular type of cloth is not material to this invention and may be chosen, from those available, by the skilled mechanic.

The duster cloth is originally in the form of an elongated rectangle whose width is equal to a substantial portion 60 of the length of the bar 13 and whose ends are turned over and sewn into seams 21 which are overlapped and connected together by snap fasteners 22. The opposite long side edges of the cloth band are also turned over and seamed at 23 with conventional sewn seams. It may also 65 have a splicing seam shown at 28, if one is needed.

The band is normally passed over the bar 13 before the snap fasteners are connected. Thereafter, the snap fasteners are connected to form the endless band which then hangs vertically downwardly a sufficient distance so that 70 its bottom portion 24 rests or laps for about two inches or so and drags upon the top surface of the belt 12 (FIG. 4).

The frictional drag between the band portion 24 and the top surface of the belt 12 is normally less than the load and friction resulting from the contact between the band 20 and the bar 13. Thus, normal movement of the belt 12 does not disturb the band. However, when a bowling ball B (see FIG. 3) rolls down the lane and strikes the bumper 16, the shock transmitted to the bar 13 moves or rotates or shifts slightly and jars the cloth in contact with it so as momentarily to free the cloth to some extent from the bar and thus reduce its frictional contact. The rotation of the bar 13 may also rotate the band slightly. Thus, at that moment, the drag between the band portion 24 and the belt 12 is sufficiently great to pull the band and cause it to rotate about the bar 13 in the direction of arrow 25 (see FIG. 4). Hence, each time the ball strikes the bumper, the cloth band is advanced by the coaction of the shock of the ball striking the bumper and being transmitted to the bar 13 and the frictional drag of the horizontal belt 12. Thus, the cloth portion 24 constantly changes so that a clean portion of the band is constantly presented to the belt surface. The movement of the band is slight so that the band would complete a complete revolution only after a considerable period of time and a considerable number of impacts of the ball B with the bumper 16.

As illustrated in FIGS. 1 and 3, the pins in moving upon conveyor 12, pass into and under band portion 24 and are dusted, with the result that when they roll into the pin setting mechanism, they are substantially clean and free of dust and thus do not carry dust and dirt into the pin setting mechanism. Likewise, the conveyor belt is constantly dusted by portion 24 to keep it clean at all times. The band, because of its side seams 23, which increase the friction between the side edges of the band and the bar 13, and also because of the horizontal seam 21, which functions to some extent as a horizontal stiffener, does not bunch up along the bar 13, but remains flat relative to the bar, as illustrated in FIG. 4.

This invention may be further developed within the scope of the following attached claims. Accordingly, it is desired that the foregoing description be read as being merely illustrative of an operative embodiment of this invention and not in a strictly limiting sense.

I now claim:

1. Apparatus comprising an endless constantly moving horizontal conveyor belt arranged in a pit at the rear end of a bowling alley for receiving and carrying bowling pins struck down by a bowling ball rolled down the alley, a horizontal bar arranged transverse of and at a considerable distance above the conveyor belt, resilient rubber bushings mounting the bar at its ends for reciprocal rotation so that it can rock back and forth a few degrees; a back-stop bumper arranged between the bar and the belt for stopping a rolling bowling ball and absorbing the impact thereof; vertical arms fixedly connecting said bumper to the bar whereby horizontal movement of the bumper due to ball impact causes sudden rotary movement of the

bar a few degrees; a bowling pin dust cloth formed as an endless band of a width approximately the length of the bar and loosely passed over and looped around said bar to rest upon it, with the band being of a vertical length to hang vertically beneath the bar and loosely drag its lower end for about two inches upon the top surface of the belt, with the frictional drag of the belt against the lower part of the band normally being less than the frictional contact between the bar and the band whereby the cloth does not normally shift on the bar, the cloth being shifted so that the cloth band portion which drags upon the belt is changed by movement of the band around the bar a slight amount in response to the shock of a ball striking the bumper, said shock being transmitted to the bar to rotate it a few degrees and also momentarily reduce the normal friction between the band and bar, whereupon the frictional drag of the moving conveyor belt upon the band drags the band portion in contact with the belt and thus advances or rotates the band relative to the bar.

5 2. Means for dusting bowling pins passing through and being handled by an automatic bowling pin setter in a pit at the end of a bowling alley, including a constantly moving endless conveyor belt arranged in said pit in horizontal alignment with the end of the wood floor of the 10 bowling alley to receive pins struck down thereon and for conveying said pins in the pit from the floor to a means for replacing the pins upon the floor in proper order, and including a horizontal bar arranged considerably above and transverse to the belt, resilient rubber bushings mounting the bar at its ends for reciprocal rotation so that it can 15 rock back and forth, and a ball bumper fixedly secured to the bar and arranged above and transverse to the belt but below the bar for stopping a rolling ball and receiving the impact of the ball, with such impact being transmitted 20 from the bumper to the bar; said first-mentioned means comprising an endless cloth band loosely passed over and looped around said bar to rest upon the bar and covering a substantial length of the bar and hanging free downwardly with its free end dragging on the belt and with the 25 frictional drag of the belt against the band normally being less than the frictional contact between the cloth and the bar; the band being advanced around the bar to change its portion in contact with the belt in response to the 30 shock of a bowling ball striking the bumper, said shock 35 being transmitted to the bar to momentarily reduce the frictional contact between the band and the bar and hence permit the frictional drag of the moving belt to drag the band and advance it a slight amount.
